SUPPORTING TRIPOD FOR A HOSIERY LINKING MACHINE

Cesare L. Conti, 18 via Varese, 20121 Milan, Italy

Filed Nov. 13, 1970, Ser. No. 25,971

Claims priority, application Italy May 18, 1970

Term of patent 14 years

Int. Cl. D15—08

U.S. Cl. D47—5

FIG. 1

FIG.2

FIG. 1 is a side perspective view of a supporting tripod for a hosiery linking machine, showing my new design, the side opposite that shown being substantially similar thereto; and

FIG. 2 is a top plan view thereof.

I claim:

The ornamental design for a supporting tripod for a hosiery linking machine, substantially as shown and described.
